UNITED STATES PATENT OFFICE.

LEO SCHÜLER, OF BERLIN-LICHTERFELDE-WEST, GERMANY.

METHOD OF OPERATING ELECTROMAGNETIC STRIKING-TOOLS BY MEANS OF ALTERNATING CURRENT.

1,115,251.

Specification of Letters Patent.

Patented Oct. 27, 1914.

Application filed August 30, 1912. Serial No. 717,873.

To all whom it may concern:

Be it known that I, LEO SCHÜLER, a citizen of the Empire of Germany, residing at Berlin-Lichterfelde-West, in the Empire of Germany, have invented a new and useful 5 Method of Operating Electromagnetic Striking-Tools by Means of Alternating Current, of which the following is a specification.

My invention relates to a new method of 10 operating electromagnetic striking tools by means of alternating current with the aid of synchronous interrupters, whereby a satisfactory working of the striking tools is obtained, while all sparks during the interruption of the current are avoided.

I will now proceed to describe my invention with reference to the accompanying drawings, in which—

Figure 1 is a diagram of a plant comprising 20 a source of alternating current, a positively driven interrupter and an electromagnetic striking tool, Figs. 2 to 5 are diagrams which will be hereinafter referred to, and Figs. 6 to 8 show modifications of the generator in Fig. 1.

Fig. 1 diagrammatically illustrates a plant comprising an alternating current generator G, a positively driven interrupter I and a known electromagnetic striking tool T. Of course more than one tool may be inserted in the circuit.

The electromagnetic striking tool T shown comprises a casing 1 with a central tubular magnet 2, a coil 3 in the space between the casing 1 and the magnet 2, a tool (chisel) 4 loosely inserted with its shank in the magnet 2, a cover 5, a hammer 6 rocking about a pin 7, engaging through a hole 8 in the cover 5 and adapted to strike the upper end of the tool 4, a helical spring 9 for connecting a rear arm 10 of the hammer 6 with a lug 11 on the casing 1 and normally holding the hammer 6 in the detached position, and a handle 12 for pressing the tool 4 against any work-piece similar to any known pneumatic tool.

The alternating current supplied from the generator G of any known construction and circulating in the circuit 13, 14 energizes by 50 means of the coil 3 the magnet 2 for attract-

ing the armature 6 serving as a hammer downward, whereby a blow on the chisel 4 is produced. After the blow the circuit must be opened for returning the hammer 6 to its initial position under the action of the 55 strained helical spring 9.

For periodically closing and opening the circuit a positively driven interrupter I of any known construction is employed. For example the interrupter I may consist of a 60 disk 15 of insulating material fastened on a shaft 16, which turns in suitable supports 17 and is connected with the armature shaft 18 of the generator G by means of an endless chain 19 and chain wheels 20 and 21. A 65 contact segment 22 is fastened in a suitable recess of the disk 15 and extends over a certain portion of the periphery. Two adjustable contact brushes 23 and 24 of any known construction are shown as provided on the 70 frame (not specifically shown) of the interrupter I.

For the sake of clearness the electromagnetic tool T is shown to be proportionally large in relation to the alternating current 75 generator G and the interrupter I.

In order to better explain the method according to my invention it is necessary to first describe here certain phenomena which occur on an alternating current being closed 80 (vide for example Linke, *Elektrotechnisches Archiv*, 1912, No. 1).

The diagram in Fig. 2 illustrates the curves of the tension E and of the strength of the current i in a purely inductive circuit 85 permanently connected with a source of alternating current. The curve i is at the same time to represent the variations of the magnetic field, the current strength and the field strength being for the sake of simplicity 90 assumed to stand in a proportion to one another. The ordinates drawn of the curves are at a distance from one another representing two thousandths of a second and consequently the ordinates correspond to a frequency of 50 cycles per second of the alternating current. When in such a circuit a synchronously driven interrupter is inserted, which always closes the circuit at the instant 95 5 (where the tension E reaches its positive 100

maximum) and again opens it at the instant 15 (where the tension E reaches its negative maximum) after which the interrupter closes the circuit at the instant 25 (not shown) and 5 so on, then magnetic impulses of the amplitude 2.5 and the period of 1/100 seconds will be produced, which alternate with pauses of also 1/100 seconds each. When, however, the circuit is closed at the instant 0, the curve i 10 representing the current and the field will have the shape shown in Fig. 3, from which it will be seen, that the maximum of both the current and of the field will amount to 5 and the duration of the magnetic impulse will 15 amount to 2/100th seconds, which means that a much greater quantity of magnetic energy is now available. It would therefore be preferable to always close the circuit about at the moment where the tension is 20 equal to zero and to again open the circuit only after about two waves of tension, that is after a full period, since the maximum of the magnetic effect will be thereby obtained. The increase in magnetic effect and in current 25 produced by closing the inductive current at the moment when the tension is zero is already known and had hitherto been regarded as an unwelcome disturbance, while according to my invention it is utilized. The 30 increase of the duration of the magnetic impulse is of special importance, since the period of 1/100th seconds would not be sufficient for imparting a considerable speed to a hammer of the required weight.

35 As can be seen from Fig. 3, at the moment 20 not only the current, but also the tension has the value zero, so that an interruption of the circuit perfectly free from sparks can be effected. I have found, that the sparkless 40 interruption of the circuit will always be possible, when the time-interval during which the circuit is closed is nearly symmetrically situated with regard to a zero-point (10) of the E. M. F.-curve as in this 45 case the magnetic field is built up by one wave of tension (or a part of it) and caused to disappear by the corresponding part of the following oppositely directed wave of tension, so that the magnetic field and in 50 consequence the exciting current is nearly zero at the moment of interruption.

55 The curve i refers to a purely inductive circuit, which however is impossible, since always a certain resistance is present. When 55 taking into account this resistance, the actual current will be represented by the curve i' , so that the interruption of the current free from sparks can only take place about at the instant 18.

60 The curves in both diagrams Figs. 2 and 3 relate to a circuit with constant self-induction, say to a choke-coil. When a striking tool T , such as shown in Fig. 1, is employed, then the variability of the self-induction

caused by the motion of the armature 6 must be taken into account. The curve of the current i and that of the magnetic field B will then assume shapes such as are represented in Fig. 4. The break of the curve i at the instant 10.5 indicates the moment at 70 which the armature 6 strikes the upper end of the tool 4. One might think, that the current should be interrupted shortly afterward, however, a spark would be produced. For this reason it is necessary to wait until 75 the current (and the magnetic field) is so to say "sucked" from the apparatus under the influence of the negative wave of tension, and then to open the circuit, say at the point of time 17.5. A strict adherence to this 80 moment, however, is not of special importance, since the strength of current between the points of time 17 and 23 is so slight, that an objectionable sparking cannot take place at the interruption of the current. The long 85 duration of the approximately sparkless interval is a special advantage of the new method to be hereinafter described.

The apparatus cannot be operated in such a manner, that the circuit is always closed at 90 the commencement of say the positive wave of tension and again opened shortly before the end of the negative wave, since sufficient time must be left to the armature for returning to its initial position under the action of 95 a spring as in Fig. 1 or of any other means, for example a second electromagnet. In order to obtain the time required for the return of the armature, I so arrange the positively or synchronously driven interrupter I, 100 that it does not close the circuit at the commencement of every positive wave of tension, but closes only at the commencement of every second or third, etc., positive wave of tension. When for example for the frequency of 50 the interrupter makes contact for every third period during 18/1000th seconds, then 42/1000th seconds would be left for the return of the armature, which is in accordance with practical conditions. 110 However, the circuit may also be closed alternately at the commencement of each positive wave and at that of the next but one negative wave, so that 32/1000th seconds are left for the return. In the former case, the 115 hammer would make $\frac{50}{3} = 16 \frac{2}{3}$ blows per second, and in the latter case $\frac{50}{2} = 20$ blows per second. These are practical values, such as they are found with known pneumatic hammers. The usual frequency of 50 is 120 therefore suitable for the operation of striking tools according to the present method.

The positively driven interrupter may be of any known construction, it may have rotary contacts similar to Fig. 1 or oscillatory 125 contacts. In all cases it is only necessary, that the moments of the closing and opening of the circuit can be adjusted, so as to avoid

all sparking. When the interrupter I is disposed separately from the generator G, as in Fig. 1, it must be positively driven from the latter, for example by means of a chain 5 gear 19, 20, 21, as described, or by means of gear wheels such as those shown at 32 and 33 in Fig. 7. Or the interrupter I may be coupled with the shaft 18 of the generator or a synchronous motor or secured on this shaft. 10 In the latter case the number of poles of the generator must suit the circumstances. When for example the circuit is to be kept closed for one period and open for two periods, the generator G or the synchronous 15 motor will require to have six poles such as those shown at 34 in Fig. 8 and the interrupter-disk 15 will have to make contact during one third of the revolution. When the interrupter disk 15 is driven not by the generator G but by a synchronous motor, the latter must have six poles similar to those shown at 20 34 in Fig. 8. For other numbers of poles the ratio of the chain wheels 20, 21 or the gear wheels 32, 33 will have to be correspondingly 25 selected.

When the circuit is invariably closed at the commencement of a positive (or negative) wave of tension, the apparatus will be operated by means of current-impulses of 30 the same sense. In this case a rectifier of any known construction, for example an electrolytic valve cell 25 or a mercury vapor rectifier may be employed for switching the current on and off, so that all sparks are 35 absolutely avoided. As the valve cell 25 would close the circuit at the commencement of each positive wave of tension and this is not always desirable, a mechanical interrupter I must often be employed in addition to the 40 valve cell. This interrupter should be so adjusted as to open the circuit at a time, when no current passes through, so as to avoid sparking, and to keep the circuit open as long as desired.

45 I have found, that it is not always advisable to open the circuit at the moment when $i=0$ (that is at the instant 17.5 in Fig. 4), since a residual magnetism may be left in the magnet coil 3 of the electromagnetic 50 striking tool, which residual magnetism under circumstances would hold fast the armature. In such cases it is preferable to open the circuit not at the instant 17.5, but a little later, so as to permit a negative 55 pulse to enter the magnet for canceling the residual magnetism. To this end the moment of interruption can be shifted from the point 17.5 to the point 22.5, where again $i=0$. Or the circuit might be opened at the 60 instant 17.5 (which in the case of an electrolytic rectifier is effected automatically) and the interrupter might be permanently bridged over by a comparatively high resistance 26, which permits a slight current

to pass over for canceling the residual magnetism. It is also possible to operate the electromagnetic striking tool in the described manner without the employment of any interrupting device. It is necessary for this purpose to employ a generator of a 65 special construction for producing an alternating current corresponding to the curve of tension shown in Fig. 5. Such a generator is for instance shown in Fig. 6. The armature 27 is provided with windings 28 70 and 31, which are connected to the sliprings 30 and 29, from which the current is collected by brushes. As will be seen from the figure, the armature coils 28 and 31 cover only a small part of the circumference of 75 the armature, and the field poles N and S also extend only over a small arc. When the armature rotates, a positive and a negative tension-wave will be induced in the armature-coils, when these pass under the 80 poles, and no tension at all will be induced as long as the armature-coils rotate in the space between the poles. The relative duration of the tension-impulses and of the 85 pauses can be selected at will by altering the 90 angle covered by the armature-coils and by the poles.

It will now be seen, that my improved electromagnetic striking tool is operated in the same manner, whether it be connected to 95 the special generator producing a wave-shape such as shown in Fig. 5 or to an ordinary generator operating in conjunction with an interrupter such as shown in Fig. 1. In both cases I employ a succession of strong 100 impulses (for the working stroke), weak impulses of the opposite sense (for canceling the residual magnetism) and pauses without current (for the return of the armature).

I claim:

1. The method of operating an electromagnetic striking tool by means of alternating current, which consists in intermittently supplying current to the magnet coil during time-intervals approximately equal 110 to one cycle, each time-interval being symmetrically situated to one zero-value of the E. M. F. wave, so that the magnetic field for attracting the armature is not only formed, but also permitted to disappear within said 115 time-interval.

2. The method of operating an electromagnetic striking tool by means of alternating current, which consists in connecting the tool to the supply circuit at the instant when 120 the E. M. F. of said supply is approximately zero, maintaining the connection during a time-interval approximately equal to one cycle and interrupting the circuit during a time-interval at least equal to one cycle.

3. The method of operating an electromagnetic striking tool by means of alternating current, which consists in supplying

105

125

to the magnet coil an alternating current the tension curve of which shows groups of one positive and one negative wave and intervals between these groups in which the tension is approximately equal to zero, so as to obtain strong impulses for the working stroke of the armature, weak impulses of the

opposite sense for canceling the residual magnetism and pauses without current for the return of the armature.

LEO SCHÜLER.
